UNITED STATES PATENT OFFICE.

HERMAN B. FERGUSON, OF PHILADELPHIA, PENNSYLVANIA.

DESIGN FOR A GARMENT BAG.

Application filed April 10, 1928. Serial No. 26,214. Term of patent 3½ years.

To all whom it may concern:

Be it known that I, HERMAN B. FERGUSON, a citizen of the United States, and a resident of Philadelphia, county of Philadelphia, State of Pennsylvania, have invented a new, original, and ornamental Design for Garment Bags, of which the following is a specification, reference being had to the accompanying drawing, forming a part thereof.

In the accompanying drawings:

I claim:

The ornamental design for a garment bag as shown.

HERMAN B. FERGUSON.
